UNITED STATES PATENT OFFICE.

ALVA S. MERRIETT, OF KANSAS CITY, KANSAS.

MOLD FOR CONCRETE WALLS.

No. 799,914.

Specification of Letters Patent.

Patented Sept. 19, 1905.

Application filed April 10, 1905. Serial No. 254,625.

To all whom it may concern:

Be it known that I, ALVA S. MERRIETT, a citizen of the United States, residing at Kansas City, in the county of Wyandotte and State of 5 Kansas, have invented certain new and useful Improvements in Molds for Concrete Walls; and I do declare the following to be a full, clear, and exact description of the invention, such as will enable others skilled in the art to which it 10 appertains to make and use the same, reference being had to the accompanying drawings, and to the figures of reference marked thereon, which form a part of this specification.

My present invention relates to a mold for 15 concrete walls, and more particularly to a mold for forming walls for dwellings and similar structures in which a continuous air-space in the wall is desired, and to a core for forming the hollow in the wall.

20 It is the object of my invention to provide a device of the class described which is simple and economical in construction and comprises features of novelty and utility and improved details of structure which will presently be 25 fully described, and pointed out in the claims, reference being had to the accompanying drawings, forming part of this specification, in which like reference-numerals refer to like parts throughout the several views, and in 30 which—

Figure 1 is a view in side elevation of several sections of my improved mold supported on a portion of completed wall. Fig. 2 is a top plan view of same, showing the cores for 35 forming the hollow in the wall. Fig. 3 is a transverse vertical section on the line xx , Fig. 2. Fig. 4 is a detail view of the channel brace-bar in the assembled mold. Fig. 5 is a detail view of a wedge used in binding the 40 members of the brace-bar together. Fig. 6 is a detail view of the stay upon which the ends of the mold-section rest. Fig. 7 is a detail view of a keeper used in retaining the mold-sections in position after the section of a lower 45 tier have been removed from the wall. Fig. 8 is a detail view of a modified form of brace-bar. Fig. 9 is a perspective view of the core used in combination with the mold. Fig. 10 is a detail view of the core-cover. Fig. 11 is 50 a top plan view of the core shown in Fig. 9. Fig. 12 is a longitudinal vertical section on the line YY , Fig. 11.

Referring more in detail to the drawings, 2 and 3 designate the front and back plates of 55 my mold, which are shown mounted on a portion of previously-formed wall 1. Said plates

have offsets 4 at each of their lower ends, which rest upon stays 5, laid transversely on said wall. Plates 2 and 3 are further provided at the top and bottom of each of their ends 60 with lugs 6, which project outwardly and have inwardly-turned lips 7, forming recesses into which the flanges of the channel brace-bars 8 are adapted to fit. Bar 8 is composed of two strips of ordinary channel-iron, each strip having a vertical portion 9 and horizontal portions 10, one of said horizontal portions overlapping the other and each having a series of perforations therein adapted to register with each other and in which a bolt 12 is secured 70 when it is desired to lock the members of the bar together. By having a plurality of perforations in each member the bar may be adjusted to fit molds of different widths. While the nut of bolt 12 may impinge directly against the face 75 of the bar member, I prefer to have said bolt extending through a slot 13 of a wedge-shaped tightening-block 14, which fits within the channel of the upper bar member. When block 14 is used, the members are bound together, as described, and further tightened by forcing block 14 forward in its channel, thereby binding said members still closer together in the manner readily apparent. As before stated, the plates 2 and 3 rest upon a 80 stay 5, which extends transversely across the lower portion of the wall and on the upper edge of the previous mold-plates, and within the ends of stay 5 are perforations 15, through which the vertical portions of bar 8 extend 85 after passing through the recesses formed by lugs 6. The mold-plates are in this manner held firmly together and in alignment while material is being fed to and hardened therein. If so desired, a number of tiers of the wall 90 may be formed without removing the front and back plates, each tier being mounted directly upon the preceding in order to give the mold composition time to harden. When this is done, however, it is necessary to remove 95 the brace-bars 8 in order that each succeeding tier of mold-sections may be placed in position. When said bars are removed, a keeper 16, preferably of the form shown in Fig. 7, is inserted into the opening 15 in stay 100 5. The head 16^a of said keeper supports it in position and retains said front and back plates in the same relation to each other as before the brace-bars were removed.

With the mechanism described a solid wall 110 may be formed; but for building purposes it is advisable for several reasons to provide an

air-space or hollow within the wall. For this purpose I provide the core shown in detail in Figs. 9 to 12, which comprises a body portion 17, to the ends of which are hinged gates 18 and 19, having end portions extending at right angles to body 17 and side portions parallel with said body, said side portions having beveled edges which meet slightly to one side of the transverse center of the core. Body 17 is straight throughout its extent and is provided at its end with hinge members 20, to which similar members on the ends of gates 18 and 19 are pivoted, said ends having curved portions thereon which fit smoothly against the ends of said body when the core is in its set position. Attached to the body 17 and to one of the gates 18 or 19 are spreaders 21, having perforated upper horizontal portions 22, which extend over the sides of the mold-plates and are held in position by pins, which extend through said perforations and impinge against the outer surface of said plates. If so desired, the spreaders 21 may be dispensed with and latches 23 mounted on the inside of said core. When in its set position, the core is oblong, as shown in Figs. 9 and 11. After the concrete has been set around the core and it is desired to remove same the spreaders are released and the gates 18 and 19 collapsed inwardly, as indicated in dotted lines in Fig. 11, such inward collapse tending to decrease the length and breadth of the core in order that it may be drawn from the concrete, leaving a recess in each block, which registering or partially registering with similar recesses in the blocks in former and succeeding tiers form a continuous hollow throughout the wall. The gates 18 and 19 are made in sections, with a portion of the ends of the sides overlapping the hinged ends. By providing each section with a series of perforations the parts may telescope over each other and be secured together by bolts, which extend through the perforations, and a core of a desired width provided. In Fig. 10 I show a cover for the core comprising two metal plates, one of which overlaps the other and both being provided at each end with a series of perforations. By sliding the parts of the cover away from or toward their center said cover may be adjusted to fit cores of varying widths, the two parts of the cover being secured together by a suitable bolt when in the desired relation to each other.

In the operation of my device the mold-sections are mounted, as described, on a suitable foundation, any convenient number of sections being placed in alinement to form a lower tier of the wall. With the mold-section in position the cores are placed therein, with one of their end offsets resting on a stay-plate supporting the ends of adjoining mold-sections. With the mold-section in position concrete is fed thereto around the cores and tamped, if desired, or when it is in a flowing

condition it is left to harden and the second tier of sections mounted on the first, as illustrated in Fig. 1. In forming each succeeding tier the brace-bars are removed and the keepers (shown in Fig. 7) are inserted into the 70 perforations in the stay-plates to retain the front and back plates in position. Other stay-plates are laid across the middle of the top of the sections and front and back plates mounted thereon, so that when the cores are placed in 75 position each end of the cores will be over a portion of two of the adjacent recesses in the former tier. By the removal of the stay-plate 5 a transverse opening is provided through the wall, which is connected with the 80 recesses left by the cores, owing to the ends of the cores in adjacent mold sets resting on the stay, as before described, making a connected horizontal hollow in the adjoining halves of two wall-sections, the hollow being 85 broken in the middle of each section by the space left between the inner ends of the cores in each mold set. As the end of each succeeding mold set is posited over the middle of the preceding one a transverse opening is 90 provided directly over the closed portion in the middle of the former section, so that while the cores, being set in a vertical line, leave a direct vertical hollow the transverse openings are in a direct vertical line only in 95 alternate tiers, with the horizontal hollow broken in the middle of each mold-section, the only means of air communication between the recesses in a wall-section being through the vertical recess of a succeeding section through 100 the transverse recess left by the stop-plate in said succeeding section and down through the second cored recess. In this manner a tortuous horizontal and direct vertical air-passage is formed throughout the wall. When 105 the concrete within the lower tier has been sufficiently hardened, the mold-sections are removed and the stay-plate drawn, the ends of the opening formed by the withdrawal of said plates being closed with mortar, while 110 the inner portion of the opening forms an additional horizontal connection between the recesses left in two adjacent mold-sections.

While I have specifically described my device, I do not wish to be understood as limiting myself to the exact details of structure herein shown and described, inasmuch as the same may be varied without departing from the spirit of my invention.

Having thus described my invention, what 120 I claim as new therein, and desire to secure by Letters Patent, is—

1. In a device of the class described, the combination with a set of front and back plates, of lugs on the ends of said plates, stay-plates 125 supporting said front and back plates, and a brace-bar extending through recesses in said lugs and through perforations in said stay-plates, for the purpose set forth.

2. A device of the class described, compris- 130

ing front and back plates having lugs adjacent to the top and bottom of the outer surface and near the ends thereof, inwardly-extending lips on said lugs forming recesses between same and the bodies of the lugs, and brace-bars adapted to fit within the lug-recesses of adjacent plates, for the purpose set forth.

3. In a device of the class described, the combination with a series of front and back plates, arranged in sets, of stay-plates supporting the abutting ends of each of said sets of plates, each of said plates being provided with an end offset of a depth of the thickness of said stay-
10 plates, to provide horizontal alinement of said plates when supported on said stay-plates, and means for spreading said front and back plates apart, for the purpose set forth.

4. In a device of the class described, the combination with a series of front and back plates, arranged in sets, of wedge-shaped stay-plates supporting the abutting ends of each of said sets of plates, and brace-bars fitting over said front and back plates, for the purpose specified.

5. In a device of the class described, in combination with suitable front and back plates arranged in sets, of angling channeled brace-bars fitting over the abutting ends of adjacent sets of said front and back plates, said brace-bars being arranged in pairs with the hori-

zontal portion on one member overlapping the horizontal portion of the other member, each of said members having a series of perforations in its horizontal portion, a wedge-shaped tightening-block fitting within the channel of the upper bar, and a bolt extending through a slot in said tightening-block and through registering perforations in said brace-bar members, for the purpose set forth.

6. In a device of the class described, the combination with the body of the mold of a core, comprising a body-plate, and plates hinged to said body-plate, and side portions on said end plates completing the core.

7. In a device of the class described, the combination with the body of the mold of a core, comprising a body-plate, end plates having curved edges hinged to said body, and side plates adjustably secured to said end plates, substantially as set forth.

8. In a device of the class described, the combination with the body of the mold, of a core comprising the body-plate 17, the end plates 18 and 19, and side plates suitably carried by said end plates, substantially as set forth.

In testimony whereof I affix my signature in presence of two witnesses.

ALVA S. MERRIETT.
